(57) **CLAIM**

The ornamental design for a radio transceiver, as shown and described.

DESCRIPTION

FIG. 1 is a front elevational view of a radio transceiver showing my new design;

FIG. 2 is a rear elevational view thereof;

FIG. 3 is a side view, taken from the left side of FIG. 1;

FIG. 4 is a side view, taken from the right side of FIG. 1;

FIG. 5 is a top plan view thereof;

FIG. 6 is a bottom plan view thereof; and,

FIG. 7 is a perspective view thereof.

The broken line showings of the displayed status of the transceiver as "ON" in FIG. 1 and of the "KT" logo in FIGS. 1 and 7 are for illustrative purposes only and form no part of the claimed design.
